UNITED STATES PATENT OFFICE.

HORACE G. STONE, OF CHICAGO, ILLINOIS.

TRACTOR WHEEL.

Application filed May 19, 1922. Serial No. 562,084.

To all whom it may concern:

Be it known that I, HORACE G. STONE, a citizen of the United States, residing in Chicago, in the county of Cook and State of Illinois, have invented a new and useful improvement in Tractor Wheels, of which the following is a specification.

My invention relates in general to traction wheels of the type shown and described in my Patent No. 1,399,413, granted Dec. 6, 1921, in which a series of plugs is provided around the periphery of the wheel and adapted to be projected by a gravity member only when the part of the wheel in which they are contained approaches the ground, the particular object of the present invention being the provision of means for positioning and holding the gravity member in an inoperative position within the wheel when the latter is traveling over smooth ground and it is not desired that the plugs shall be projected for traction purposes.

As stated in my patent above referred to, the traction wheel which I provide is adapted to overcome the difficulties ordinarily experienced in the propelling of tractors by the use of means of the foregoing character to prevent slippage of the wheel, the arrangement also permitting the cleaning of the smooth wheel surface and the plugs themselves during upper part of the travel of the wheel. When the wheel is traveling over smooth ground, or upon pavements, it is, of course, undesirable that the traction plugs should be projected and, in order to prevent the necessity of complete removal of the gravity member under such conditions, I provide means for removing said member from contact with the inner ends of the plugs when desired, and holding it in a convenient position, preferably concentric with the wheel, so that it does not impede the progress thereof.

A further object of the invention is the provision, in a construction of this type, of supporting means for the gravity member of such character that said member may be lifted from its operative to its inoperative position by mere successive placement of the supports as the wheel is slowly rotated, the supports for this purpose being preferably provided at three points about the center of the wheel.

Another object of the invention is the provision of a support for the gravity member, which will permit said member to move

to its operative position by the withdrawal of merely a single support and slight rotation of the wheel, it being possible, in this manner, to remove each of the supports 60 when no load is imposed thereon.

Still another object of the invention is the provision of simple devices for accomplishing the purpose stated, which will be inexpensive and adapted for easy insertion, or 65 withdrawal, so that they may or may not be used, in accordance with rapidly changing requirements.

Other objects and advantages of the invention will be apparent as it is better understood from the following description, which, taken in connection with the accompanying drawings, discloses a preferred embodiment thereof.

Referring to the drawings, Figure 1 is a side elevation of a traction wheel in which my invention is embodied, a part of one of the side plates being broken away and certain parts being shown in section for convenience of illustration;

Fig. 2 is a similar view with the gravity member held in its inoperative position; and

Fig. 3 is a partial transverse section, showing the parts in the position assumed in 85 Figure 2.

The traction wheel shown upon the drawing, for purposes of illustration, is formed with an outer rim 11, connected by means of side plates 12 with a hub 13 mounted on 90 an axle 14, the wheel being adapted to be propelled by power applied through a sprocket wheel 15 secured by bolts 16 with the side thereof. The rim 11 is connected by means of bolts 17 with the side plate 12 and a second band 18, of similar formation, is provided a short distance inwardly from said rim and connected by means of bolts 19 with said side plates 12. Extending through apertures in the rim 11 and band 18 are plugs 20, which are freely slideable through said apertures and upon which are mounted springs 21 having one end bearing against the interior of the rim 11 and the other against collar plates 22 provided on 105 the plugs and held by pins 23 at a point which causes the springs to hold said plugs normally retracted to an extent which disposes their outer ends flush with the periphery of the wheel. This arrangement also 110 prevents the projection of the plugs to too great an extent and it is obvious that the

springs may be of any desired tension, according to particular requirements.

A ring 24 is provided within the wheel and is adapted to bear upon the inner ends 5 of the plugs 19 when the part of the wheel in which they are contained approaches the ground, as illustrated in Figure 1. In this manner, the plugs are caused to enter the ground to provide the desired traction. The 10 plugs may be arranged in any desired number and position in the rim and inner band 18, being shown in the drawing in a double row and in staggered relationship.

The ring 24 comprises a heavy gravity 15 member which is adapted to roll within the wheel directly above the portion thereof which is in contact with the ground, thereby projecting the plugs 20 for traction purposes. By reason of the springs 21, said 20 plugs are held in retracted position, as heretofore stated, excepting when said gravity member bears upon their inner ends as they approach the ground, said member, therefore, serving to provide suitable traction 25 surface conditions on the exterior of the wheel successively in the areas where needed and permitting the traction devices and periphery of the wheel to be cleaned when they are above the ground.

30 A mud scraper 25 is mounted upon the tractor frame and adapted to remove the mud from the periphery of the wheel when the latter is in its upper position with the plugs 19 retracted. It is obvious, also, that 35 the retraction of the plugs effectively cleans them and, in this manner, the entire wheel is continuously and automatically cleaned in operation.

In order that the ring 24 may be held out 40 of operative position when the tractor is traveling over smooth surfaces, I provide a series of supports 26, which, in the present instance, comprise bolts extending through apertures 27 in the side plates 12. By providing these supports at three points about the center, or hub of the wheel, it will be manifest that the ring may be positioned within the supporting pins 26 by first inserting two pins in the two apertures shown 45 in upper or unobstructed position in Fig. 1, and inserting the other after the wheel has been turned to the position shown in Fig. 2. Thus no lifting is required and the ring, or 50 gravity member, may be rapidly and easily moved from operative to inoperative position and vice versa, release being accomplished by mere withdrawal of the bolts. The ring is thus also held in concentric position, so that it does not interfere with the balance 55 or movement of the wheel.

It is thought that the invention and many of its attendant advantages will be understood from the foregoing description, and it will be apparent that various changes may 60 be made in the form, construction and ar-

rangement of the parts without departing from the spirit and scope of the invention or sacrificing all of its material advantages, the form hereinbefore described being merely a preferred embodiment thereof.

I claim:

1. A traction wheel, comprising a rim, a hub, plugs extending through said rim and slidably therethrough to and from extended and retracted positions, springs for retracting said plugs, and a gravity member engaging the inner ends of said plugs when they approach the ground for projecting them from said rim into traction engagement with the ground, means for connecting the rim with the hub, and means for holding said gravity member out of engagement with the inner ends of said plugs when it is not desired that the latter shall be projected.

2. A traction wheel, comprising a rim, a hub, plugs extending through said rim and slidably therethrough to and from extended and retracted positions, springs for retracting said plugs, and a gravity member engaging the inner ends of said plugs when they approach the ground for projecting them from said rim into traction engagement with the ground, means for connecting the rim with the hub, and a three-point support 95 for said gravity member adapted to hold the latter out of engagement with the inner ends of said plugs during the entire rotation of the wheel, said member being adapted to be positioned within the supports by mere successive placement of the latter and normal rotation of the wheel.

3. A traction wheel, comprising a rim, a hub, traction devices normally retracted in the rim, a gravity member adapted to project said devices upon their approach toward the ground, and means for sustaining said member in inoperative position within the wheel when the latter is traveling over smooth ground, thereby preventing projection of said devices.

4. A traction wheel, comprising a rim, a hub, means for connecting said rim and hub, traction plugs freely slidable through said rim and normally retracted, a gravity member for projecting said plugs as they approach the ground, and means for supporting said member concentrically with the wheel and out of engagement with said plugs when it is not desired that the plugs shall be 115 projected.

5. A traction wheel, comprising a rim, a hub, means for connecting said rim and hub, traction plugs freely slidable through said rim and normally retracted, a gravity member for projecting said plugs as they approach the ground, and means for supporting said member concentrically with the wheel and out of engagement with said plugs when it is not desired that the plugs shall 130

be projected, said means comprising a series of bolts adapted to be successively positioned so that the ring is engaged thereby by normal rotation of the wheel.

5 6. A traction wheel, comprising a rim, a hub, means for connecting said rim and hub, traction plugs freely slidable through said rim and normally retracted, a gravity member for projecting said plugs as they approach the ground, and means for supporting

said member concentrically with the wheel and out of engagement with said plugs when it is not desired that the plugs shall be projected, said means comprising supporting members insertable through said means for connecting the hub and the rim, and said ring being movable to its inoperative or supported position by successive positioning of said members and rotation of the wheel. 15

HORACE G. STONE.
